UNITED STATES PATENT OFFICE.

GEORGE FRANK REICHMAN, OF PHILADELPHIA, PENNSYLVANIA.

WATER HEATER.

Application filed March 11, 1924. Serial No. 698,365.

It is the principal object of my invention to provide a source of hot water adapted for permanent connection with the service pipes in a dwelling, and my improvements relate to heaters including means to maintain a fire of solid or other fuel, of any kind, within in a vessel in which the water is contained and heated.

As hereinafter described, my invention includes a heater comprising three sections, respectively base, intermediate and top, fitted one on top of the other. The base section is constructed and arranged to contain and support heating means, comprising a burner for coal or other fuel. The intermediate section comprises an inner tubular shell forming a fuel and combustion chamber, surrounded by an outer tubular shell forming a water chamber between said shells. The top section, which is fitted upon said intermediate section and covers said combustion chamber, includes a central axial tube forming a flue for the products of combustion from the intermediate section, and an outer tubular shell connected with said flue tube so as to form a water chamber between said tube and shell. The water to be heated is supplied to said intermediate section and the latter is connected by a coupling pipe or pipes to the upper section and the heated water dispensed through the latter.

Said section containing the combustion chamber has heat conducting metal ribs projecting inwardly from its inner shell, into said fuel chamber, and protective lining slabs of refractory material, fitted between said ribs; whereby said inner shell is protected, by said slabs, but heat is directly conducted to said water chamber by said ribs, and such construction may be used in heaters of different forms.

My invention includes the various novel features of construction and arrangement hereinafter more definitely specified.

In said drawings; Fig. I is a front elevation of a heater conveniently embodying my improvements.

Fig. II is a vertical sectional view of said heater, taken on the line II, II in Fig. I.

Fig. III is a plan sectional view of the intermediate section taken on the line III, III in Fig. II.

In said figures; the base section 1 which incloses the ash pit 2 is conveniently formed of cast iron and provided with the hinged

door 3. Said base section is arranged to support heating means comprising a burner for coal or other fuel. For instance, said section may have grate bearings 5 at the top thereof to support the sectional grate comprising two normally stationary sections 6 upon opposite sides of the tiltable section 7; the latter having trunnions 9 and 10 respectively at its front and rear; said trunion 9 being shaped as indicated in Fig. I, to be engaged by a lever wrench to rock it.

The intermediate heater section 12, which is also conveniently formed of cast iron, comprises the inner cylindrical shell 13 enclosing the fuel chamber 14 and the combustion chamber 15. The outer cylindrical shell 17 is connected with said inner shell 13 as best shown in Fig. II, so as to form the water chamber 18 between them. Said intermediate section 12 has a circular series of heat conducting metal partition ribs 20 in unitary relation with, and projecting inwardly from, said inner shell 13 into said fuel chamber 14 and extending vertically to the height of the latter. Protective lining slabs of refractory material 21 are fitted between said ribs 20 in a circular series, as shown in Fig. III; whereby said inner shell 13 is protected from direct contact with the fuel 23 which is supported by said grate, but heat is directly conducted to said water chamber 18 by said ribs 20. The fuel doorway 24 extends through both said shells 13 and 17 of said intermediate section above said ribs 20 and slabs 21, and is conveniently provided with the hinged door 25.

The wrought metal top section 26 includes the annular dome 27 covering said combustion chamber 15 and in rigid connection with the single central axial tube 28 forming a flue from said intermediate section. The outer cylindrical shell 29 of said top section is connected with said flue tube 28 so as to form a water chamber 30 between them. I find it convenient to provide the upper end of said flue tube 28 with a removable and adjustable damper bonnet 32 having three branches 33, 34 and 35 respectively provided with rotary dampers 36, 37 and 38. It is to be understood that any one of said bonnet branches may be connected to said flue pipe 28 and an ordinary stove pipe be connected with either or both of the other branches leading to a chimney either directly or through auxiliary heater drums, and said

dampers be manipulated and set to control the discharge of products of combustion from said heater accordingly.

The cold water inlet 40, near the bottom 5 of said intermediate section 12, is supplied with cold water by any convenient means, for instance, the pipe 41 controlled by the valve 42 and provided with the drain cock 43. The two coupling conduits 44, respectively upon diametrically opposite sides of 10 said heater, connect the upper part of the water chamber 18 of said intermediate section 12, with the lower part of the water chamber 30 of said top section 26 and include 15 respective unions 45 by which said two sections of the heater are detachably but rigidly connected in the position shown. Said coupling conduits 44 permit the water to circulate freely in and between said sections 12 and 26 and I find it convenient to provide 20 two hot water outlets 47 at the upper end of said top section 26, from which hot water may be dispensed, conveniently through respective pipes 48 which may extend to radiators. However, it is not necessary to have 25 two coupling conduits 44 or two of said outlets 47.

I also find it convenient to provide said heater with another inlet 50 near the bottom 30 of said intermediate section 12 for connection with a pipe 51 to return the water from any radiators connected with said heater.

I have found that a heater of the type 35 in which the source of heat is within a vessel in which the water is contained and heated is most efficient if the source of heat is brought into direct contact with the inner metallic wall of the water container. However, such construction is far less durable 40 than if the metal wall adjacent the source of heat is protected by refractory material. Ordinarily, such linings are extended continuously throughout the inner circumference of such wall, with the result that although 45 the latter is rendered more durable, the efficiency of the heater is materially reduced. Therefore, as the result of extensive experiments, I have found that to provide 50 a vessel with an inner wall which is thin in some regions and thick in others and to protect the thin regions with refractory material and expose the thick regions to the source of heat, permits the necessary extent of contraction and expansion with the 55 maximum efficiency of heating operation consistent with substantially the same durability of the structure as if no portion of the inner metal wall thereof were exposed to the source of heat. Therefore, I do not 60 wish to limit myself to the embodiment of that feature of my invention in a heater of the specific construction, arrangement or type chosen for illustration herein.

Moreover, although I have found it convenient to construct a heater in accordance 65 with my invention so that a solid fuel burner may be used as the source of heat therein; it is to be understood that I do not desire to limit myself to such a burner, as other forms of burners for using oil or gas may be 70 employed.

Therefore, I do not desire to limit myself to the precise details of construction and arrangement herein set forth, as it is obvious that various modifications may be 75 made therein without departing from the essential features of my invention, as defined in the appended claims.

I claim:

1. In a water heater, a unitary cast metal 80 section, comprising an inner cylindrical shell inclosing a fuel and combustion chamber, and an outer cylindrical shell forming a water chamber between them; heat conducting metal partition ribs projecting inwardly 85 from said inner shell, into said fuel chamber, and extending vertically to the height of the latter; and protective lining slabs of refractory material, fitted between said ribs; whereby said inner shell is protected, but 90 heat is directly conducted to said water chamber; and a fuel doorway extending through both said shells, into said combustion chamber, above said ribs and slabs.

2. In a water heater, a water container 95 formed of cast metal including inner and outer cylindrical shells with a water chamber between them and having a doorway intermediate of its height, extending radially through said water chamber; and a circular 100 series of vertical partition ribs projecting inwardly from said inner shell forming seats between them for lining slabs of refractory material; and a circular series of lining slabs, fitted between said ribs; whereby said inner shell is protected, but heat is directly conducted to said water chamber.

3. In a water heater, a water container 110 having an internal shell forming a fire pot, surrounded by a water chamber; a circular 115 series of vertical partition ribs projecting inwardly from said inner shell, forming seats between them for lining slabs of refractory material; and lining slabs of refractory material, fitted between said ribs; whereby said inner shell is protected but heat is directly conducted to said water chamber in radial planes parallel with the axis of said fire pot, and convection currents in said water chamber thereby augmented.

In testimony whereof, I have hereunto signed my name at Philadelphia, Pennsylvania, this twenty-eighth day of February, 1924.

GEORGE FRANK REICHMAN.
